UNITED STATES PATENT OFFICE.

MAX SALDIN, OF NEW YORK, N. Y., ASSIGNOR TO ESTHER SALDIN.

UNION-SUIT.

1,205,793.

Specification of Letters Patent. Patented Nov. 21, 1916.

Application filed March 17, 1914. Serial No. 825,232.

To all whom it may concern:

Be it known that I, MAX SALDIN, a citizen of the United States, and a resident of the city of New York, borough of Brooklyn, in 5 the county of Kings and State of New York, have invented a new and Improved Union-Suit, of which the following is a full, clear, and exact description.

The object of the invention is to provide 10 a new and improved union suit arranged to provide ample space for the hips of the wearer, and doubled-up front and back portions and self-closing crotch gussets.

In order to accomplish the desired result 15 use is made of a tubular body having approximately inverted U-shaped cut-out portions at both front and back, and tubular leg members having their upper portions cut out and joining the said cut-out body portions, the upper portions of the said leg 20 members being open along the inner edges to allow one upper leg portion to pass into the other and to form overlapping front and rear flaps.

25 A practical embodiment of the invention is represented in the accompanying drawings forming a part of this specification, in which similar characters of reference indicate corresponding parts in all the views.

30 Figure 1 is a front elevation of the union suit; Fig. 2 is a rear elevation of the same; Fig. 3 is a side elevation of the same with one of the leg members raised up to disclose the crotch gusset; and Figs. 4 and 5 are perspective views of the leg members.

35 The union suit consists essentially of a tubular body and tubular legs B and C, and the said parts are formed of a knitted fabric, either ribbed or plain, the body A 40 being trimmed around the neck and the arm-holes in the usual manner. The body A is provided at the front and rear lower portions with, cut-out portions A', A² of approximately inverted U shape, as plainly indicated in Figs. 1 and 2. The leg members B and C have flat upper portions cut out along the outer edges and split along the inner edges to form front and rear flaps B', B² and C', C². The front flaps B', C' lap 45 one upon the other and the rear flaps B², C² lap one upon the other, so as to form approximately U-shaped front and rear portions A³, B³, which are joined to the U-shaped cut-out portions A', A² by suitable stitching. The approximately U-shaped 50 front and rear portions A³, B³ of the legs are

of a greater size than the cut out portion of the body, so that the lower portion of the body is enlarged as shown in Figs. 1 and 2, and the said portions are rendered less elastic than the side portions of the body, due to the lapping of the flaps forming them. By thus constructing the garment the body is free to stretch, but there will be little or no stretching of the legs, and consequently 60 the flaps will always remain closed. The leg members B and C are provided along the inner edges immediately below the splits with U-shaped crotch gussets D creased along the median line to readily double up 65 in an inward direction so that when the union suit is worn the gussets D fully protect the crotch by being interlocked one with the other, as indicated in dotted lines in Fig. 2. 75

It will be noticed that by the arrangement described the garment is formed of but three essential parts, that is, the body A and the two leg members B and C, and by cutting out the body and the said leg members 80 as described they can be readily joined to form a garment having overlapping flaps both at the front and rear, and which are not liable to open owing to the U-shaped joint which extends downward and outward. 85 By inserting the crotch gussets D a full protection is had at the crotch of the wearer.

By reason of the construction shown, in which the tubular body is provided with portions extending below the hip line of the 90 garment, and to which the flaps of the leg portions are secured along an edge, the extension of the garment by the hips of the wearer will not tend to separate the flaps to any considerable extent, as would be the 95 case if the body portion did not extend substantially below the waist line.

Having thus described my invention, I claim as new and desire to secure by Letters Patent:

1. In an undergarment, a tubular body portion of a length to extend a substantial distance below the hip line of the garment and having approximately inverted U-shaped cut-out portions at the front and rear, said portions extending substantially to the waist line, leaving two depending side portions, tubular leg portions each cut out along its outer edge, thus forming front and rear flaps, the depending side portions of the body portion being secured to the edges of the cut outer edges of the leg portions and 105 110 115

the flaps of one leg portion lapping the flaps of the other at their inner edge.

2. In an undergarment, a body portion comprising a section of tubular fabric of a length to extend below the hip line of the garment and having its lower edge both front and back cut away along lines inclined upwardly and inwardly toward the vertical center line of the front and the back of the garment respectively, leaving two depending side portions, and tubular leg portions

each cut out along its outer edge to fit a cut-out side portion of the body portion and attached thereto.

In testimony whereof I have signed my ¹⁵ name to this specification in the presence of two subscribing witnesses.

MAX SALDIN.
